Patented Sept. 16, 1958

PERCOLATOR OR SIMILAR ARTICLE

John J. Balian, Hartford, Wis., assignor to West Bend
Aluminum Co., West Bend, Wis., a corporation of Wisconsin

Application March 17, 1958, Serial No. 50,045

Term of patent 14 years

(Cl. D44—26)

FIG. 1

Des. 183,507

FIG. 4

Fig. 1 is a view in side elevation of a percolator or similar article embodying my new design;

Fig. 2 is a view in front elevation thereof;

Fig. 3 is a top plan view thereof; and

Fig. 4 is a fragmentary view in rear elevation showing the percolator handle.

I claim:

The ornamental design for a percolator or similar article, substantially as shown.
